UNITED STATES PATENT OFFICE.

OSMAN S. KING, OF PAINESVILLE, OHIO.

CAR-COUPING.

SPECIFICATION forming part of Letters Patent No. 311,012, dated January 20, 1885.

Application filed June 21, 1884. (No model.)

To all whom it may concern:

Be it known that I, OSMAN S. KING, a citizen of the United States, residing at Painesville, in the county of Lake and State of Ohio, have invented certain new and useful Improvements in Car-Couplings, of which the following is a specification, reference being had therein to the accompanying drawings.

This invention relates to that class of car-couplers, in which the coupling-pin is operated by means of levers pivoted to the car, and the construction and operation will be hereinafter described, and the novel features thereof specifically set forth in the claims.

Referring to the drawings, Figure 1 is a perspective of a coupler constructed in accordance with my invention. Fig. 2 is a central vertical section. Fig. 3 is a plan of the pin-operating levers and the pin-guide. Fig. 4 is a perspective of one of the fulcrums. Fig. 5 is a modification of the operating-levers.

Like letters indicate like parts in all the figures.

A represents a portion of the frame of a car, or it may be a platform at the end of a car, to which, by suitable straps or brackets, as B, the draw-head C is connected, as usual. Upon the draw-heads there are two vertical brackets, D, provided with bearings for a guide-tube, E, mounted in said brackets, in this instance by means of trunnions or loose rivets E'. The tube E is vertically slotted upon its rear side, as at E'', for the passage of the lever F, which embraces or is otherwise suitably connected with the coupling-pin G in such a manner as to somewhat loosely support the same. In this instance the lever F is provided with an eye, F', at its free end, which is made to embrace a portion of the pin G, which is enlarged to form a shoulder, G', above the lever. The free end of the lever F is preferably cylindrical in outline, to agree in contour with the tube or guide E. The inner end of the lever F is loosely pivoted in a block, H, the ends of which are slotted vertically to receive the ends of the levers I, pivotally connected to the block by means of the pins J, having a bearing in slots, J' formed in the blocks and extending transversely therethrough. Each of the levers is mounted upon a fulcrum, K,

provided with a shoulder, K', adapted to rest upon the frame A, and the extension K'', adapted to pass through said frame-work, and by means of a split-pin, K'', or a nut, be permanently secured to the frame, and yet in such a manner as to be capable of rotation therein. The connection of the levers with the fulcrum and with the block thus far described is such that by depressing either of the outer ends of the levers I and swinging the same backward, the pin G is raised above the upper surface of the head, and the pivotally-supported guide-tube E is inclined so as to direct the point of the pin in such a manner that it will come in contact with and rest upon said upper surface just in front of the pin-hole in the head. In this manner the pin is set for coupling by concussion, without the necessity of entering between the cars, and the pivoted guide-tube serves the important function which its name indicates, of directing the pin properly. When thus set, the concussion by two cars coming together serves to force the head away from the car, and the pin, upon arriving over the hole, falls therein, to retain the ordinary coupling-link within the head. If it is desired to have the cars remain uncoupled when brought together, a backward pull on the free end of the lever I will incline the guide E, with its tube, to the front, so that the point of the pin shall be directed upon the upper surface of the head in rear of the pin-hole, and so that the concussion of the heads will not operate to throw the pin into the hole.

In connection with the pin-operating levers, I have illustrated a link-guide, L, which embodies novel features of construction and operation. It consists of a frame having trunnions L', mounted in the sides of the draw-head, the frame proper extending the whole width of the head, and provided at one, or it may be at both, sides with a bar, L'', extending from front to rear, and substantially parallel to the side of the head. Upon this bar a weight, M, is mounted, so as to slide freely from front to rear thereon, so as to rest at a point on the bar L'' in front, opposite, or in rear of the trunnion L' of the frame. At the rear end of the bar a chain or link, N, is attached, which is connected to a rock-arm, O,

of the shaft O', pivotally suspended from the frame of the car, and provided at each side of the car with a handle, O². The frame L is provided with a depending portion or arm, 5 L³, which shall act to insure the guiding of a link into the head of an approaching car, as is customary, to link-guiding frames. Now, by maintaining the frame L in a substantially horizontal position, which may be accomplished by moving the weight to or near to a point on the bar L², which is opposite or slightly in the rear of the trunnion L, it will serve to 10 guide the link into the mouth of an approaching draw-head, and when the concussion takes place between the two cars the rearward action of the head, in connection with the inertia of the weight thereon, will force the latter forward upon the bar L². It will then overbalance the rear portion of the bar L², and carry 15 the forward portion thereof downwardly out of the way from injury by the contact of the coupling-heads with each other. To again set the guiding-frame, the handle O is rotated about a quarter of a revolution, so that by 20 means of the chain N the frame is again brought to a horizontal position, and the weight, being caused to move by the momentum given to the frame, slides upon the bar L², so as to retain the frame in a desired position, as hereinbefore described. 25

If desired, a sheet-metal spring, S, can be secured to the frame of the car and made to bear against the side of the shaft or lever O', or the handle O² thereof, to retain the link-guide L in a horizontal position while the car 30 is to be coupled to another. When the spring S is provided, the sliding weight M may be used in connection therewith or may be dispensed with.

40 If desired, the lever F may be formed in one piece with and as a part of one of the levers I, the other of the levers I being flanged or slotted to embrace the end of the other lever, when, by means of a pin or a loose rivet 45 passing through both levers, they will be

suitably connected to each other for movements necessary to manipulate the pin and the guide, as above described.

Having described my invention and its operation, what I claim is—

1. The combination, with a draw-head and a coupling-pin adapted to operate therewith, of a tubular guide pivoted to suitable supports on the draw-head, and adapted to receive and guide the pin, substantially as specified. 55

2. The combination of a tubular pivoted guide mounted upon a draw-head, a pin adapted to ride in the guide, and a lever secured to the pin, and connected with suitable operating devices, substantially as specified. 60

3. A link-guiding frame pivoted to both sides of a draw-head, and provided with a bar having a sliding weight mounted thereon, substantially as specified. 65

4. The combination, with a link-guiding frame having a bar upon one side of a draw-head, and a sliding weight mounted thereon, of means for positively raising the frame to a horizontal position, substantially as specified. 70

5. The combination of the head C, provided with the brackets D, the guide-tube E, provided with the trunnion E', the coupling-pin G, lever F, and levers I, suitably mounted on a platform or frame, A, substantially as shown and described. 75

6. The combination of a tubular pivoted guide mounted upon a draw-head, a pin adapted to ride in the guide, and a link-guiding frame pivoted to the sides of said draw-head, 80 with a lever, O', spring S, and means, as described, for connecting the link-guiding frame with said lever, substantially as set forth.

In testimony whereof I affix my signature in presence of two witnesses.

OSMAN S. KING.
